J. C. TATE,
GAS BURNER,
FILED JUNE 9, 1921.

John C. Tate,
INVENTOR

Lincoln Johnson
ATTORNEY

UNITED STATES PATENT OFFICE.

JOHN C. TATE, OF OAKLAND, CALIFORNIA.

GAS BURNER.

Application filed June 9, 1921. Serial No. 476,150.

To all whom it may concern:

Be it known that I, JOHN C. TATE, a citizen of the United States, and a resident of the city of Oakland, county of Alameda, 5 State of California, have made a new and useful invention—to wit, Improvements in Gas Burners; and I do hereby declare the following to be a full, clear, concise, and exact description of the same.

10 This invention relates particularly to an improved burner.

An object of this invention is to provide a gas burner wherein either artificial or natural gas separately or in combination will 15 burn with a perfect combustion utilizing all of the heat units therein contained and incidently doing away with the generation of moisture or vapor.

20 A further object of this invention is to provide a gas burner wherein the gas and atmospheric air are separately pre-heated prior to combustion and thus partially decomposed into the elementary constituents prior to being intermixed. A further object 25 of this invention is to provide a gas burner that is superior in point of simplicity, and inexpensiveness of construction, positiveness of operation, facility and convenience in use and general efficiency. Other objects and 30 advantages will appear as this description progresses.

In this specification and the annexed drawings, the invention is illustrated in the form considered to be the best, but it is 35 to be understood that the invention is not limited to such form, because it may be embodied in other forms; and it is also to be understood that in and by the claims following the description, it is desired to cover 40 the invention in whatsoever form it may be embodied.

In the accompanying one-sheet of drawings,

Figure 1 represents a side elevation 45 through a gas burner constructed in accordance with my invention partly broken away to show the interior thereof.

Figure 2 represents an end view of Figure 1.

50 Figure 3 represents a cross-section taken through Figure 1 on the line 3—3.

Experiments have determined that gas burners are not efficient and do not produce a perfect combustion, in the burning of natural or artificial gas in the natural state 55 as contrasted with gas burners burning nat-

ural or artificial gases that have first been pre-heated, so as to raise the temperature or specific gravity thereof, where when mixed with air, which has likewise been first pre-heated, the efficiency is increased and the combustion more perfect. This invention deals particularly with a gas burner wherein either natural or artificial gas separately or in combination may be burned efficiently 60 and with a perfect combustion, accomplished by pre-heating the gas and also the atmospheric air to a very high temperature before they are permitted to mix prior to distribution. Normally where gas or fuel is 65 mixed under ordinary atmospheric conditions, it is not conducive to a good combustion, for the reason that the specific gravities of the respective elements differ. This inefficiency is overcome by pre-heating the 70 gas and air, raising the temperature and specific gravities of the products to substantially the same degree whereby a harmonious union of the elements results, forming a volatile mixture. Incidentally the pre-heating of the gas (which is of a hydrocarbon nature) and the air, tends to decompose the same into the constituent elements and a consequent mixing thereof prevents the hydrogen from passing back into 75 the air in a precipitated form and eliminates the possibility of moisture or vapor accumulating in the area adjacent where the gas is being burned.

In detail the construction illustrated in the 80 drawings, comprises a hollow mixing body generally designated by the numeral 1, which is substantially oval in cross-section and which at the front end is closed by the wall 2. A portion of the opposite end 3 is 85 opened as at 4 providing an intake port. The interior of the mixing chamber is partially divided by a division or partition member 5, extending from the rear wall 3, and above the intake port 4, to a point adjacent the front wall 2. Thus air passing through the intake port 4 as indicated by the arrows into the chamber 6 would pass around the end of the division plate 5 into the space or chamber 9 above the division 105 plate 5.

The exterior of the mixing chamber 1 is provided with a plurality of protuberances or projections 7 on its upper face having suitable discharge ports 8 therein communicating with the interior chamber 9. A fuel supply pipe 10 connects with a gas supply 110

(not shown) and is provided with a control valve 11 therein by which the volume of gas emitted from the pipe 10 may be regulated and controlled. The said pipe 10 is adapted 5 to pass over the upper face of the protuberances 7, through a suitable cored depression 12 therein provided, bended over the end 3 substantially at right angles thereto and again bended at a right angle. It thus 10 passes through the port 4 into the lower division 6 of the mixing chamber, and continues therethrough into connection with the needle control valve generally designated by the numeral 14, removably fixed in the front 15 partition 2 of the said mixing chamber. The valve member 14 comprises an elbow 13 communicating with the discharge end of the gas supply pipe where it passes through the division wall 2. Its opposite end 20 communicates with the discharge outlet 15 opening into the upper portion 9 of the mixing chamber, said opening 15 being located in a discharge nozzle 16, the exterior of which is threaded into engagement with a hollow 25 threaded bushing 17 removably located in an opening in the front wall 2. The opposite end of the nozzle 16 is interiorly threaded as at 18 so that the threaded body 19 of a needle valve 20 may be placed into 30 adjustable engagement therewith and the tapered point of said needle valve regulated relative to the discharge opening 15 by the knurled handle 21 on the exposed end of said needle valve. A suitable cap 22 is 35 adapted to be passed over the exterior of the said nozzle so as to prevent tampering with the needle valve.

Although I have shown and described a 40 particular type of gas burner and its construction, I do not wish to be limited thereto as it would be clearly within the purview of this invention to modify or re-arrange the same. This burner operates in the following manner:

45 Gas admitted through the control valve 11 passes around through the pipe 10 and from the opening 15, into the discharge nozzle into the upper division 9 of the mixing chamber 1, where it escapes to the atmosphere through the openings 8 provided in the protuberances 7. When the proper 50 amount of gas passes through the openings 8, the operator would ignite or light the same in any suitable manner and control 55 the amount of heat according to the volume of gas admitted through the regulating valve 11. The flame of combustion issuing from the openings 8 would impinge against the gas supply pipe and through conduction heat 60 the gas therein contained. Likewise through conduction, the entire body of the mixing chamber would be heated to a very high degree. The gas within the tube 10 that has 65 been heated and rarefied, moves in the direction of least resistance toward the discharge

opening 15 from whence it escapes into the interior of the mixing chamber, mixes with atmospheric air and thus issues from the said burner openings 8 in the form of a highly combustible gas. Atmospheric air 70 passing through the intake port 4 is heated by contact with the walls of the mixing chamber so that by the time it is intermixed with the pre-heated gas, the temperatures of the same are approximately constant, 75 thus insuring a harmonious union and a more intimate association of the elements and due to a higher specific gravity, a more perfect combustion is thus obtained.

Where natural and manufactured gases 80 (each of which are of different specific gravities) are distributed through the same mains, it oftentimes happens the same do not thoroughly intermix but stratify so that a gas burner regulated to burn the mixed 85 gases either burns with a roar or not at all, where the respective gases are introduced separately. Thus by passing gases of different specific gravities into an apparatus such as I have devised and pre-heating the 90 same, the temperatures are raised to a point where the same will readily unite so long as they are kept in a sufficiently heated state and are passed through the burner at a constant pressure. 95

Although I have shown a gas burner that is intended primarily to be used in combination with a radiator for heating purposes, it is my intention to utilize the same principle in burners of different shapes and constructions which may be used either individually as gas burners or in combination as described. 100

Having thus described this invention, what I claim and desire to secure by Letters Patent is:

1. A gas burner comprising a casing containing a gas mixing chamber, connected at its front end with an air passage open to the air at its opposite end, said gas mixing 110 chamber having a plurality of apertures along its upper extremity; a gas conduit arranged over said apertures and discharging into the said gas mixing chamber; and a valve for regulating and controlling the volume of gas passing through the said conduit. 115

2. A gas burner comprising a casing containing a gas mixing chamber, connected at its front end with an air passage open to the air at its opposite end, said gas mixing 120 chamber having a plurality of apertures along its upper extremity; a gas conduit arranged over said apertures, extending about one end of said casing and discharging into the opposite end of said gas mixing chamber; and a valve for regulating and controlling the volume of gas passing through the said conduit. 125

3. A gas burner comprising a casing containing a mixing chamber connected at its 130

- front end with an air passage open to the air at its opposite end, said mixing chamber having a plurality of apertures along its upper extremity; a gas conduit arranged over said apertures, extending about the rear end of said casing, into and through the air passage and discharging into the front end of said mixing chamber; and a valve for regulating and controlling the volume of gas passing through said conduit. 5
4. A gas burner comprising a casing containing a mixing chamber connected at its front end with an air passage open to the air at its opposite end, said mixing chamber having a plurality of apertures along its upper extremity; a gas conduit arranged over said apertures, extending about the rear end of said casing, into and through the air passage and discharging into the front end of said mixing chamber; an adjustable nozzle in the discharge end of said conduit; and a valve for regulating and controlling the volume of gas passing through said conduit. 10
- 20
5. A gas burner comprising a casing containing a mixing chamber connected at its front end with an air passage open to the air at its opposite end, said mixing chamber having a plurality of apertures along its upper extremity; a gas conduit arranged over said apertures, extending about the rear end of said casing, into and through the air passage and discharging into the front end of said mixing chamber; an adjustable nozzle in the discharge end of said conduit; and a valve for regulating and controlling the volume of gas passing through said conduit. 25
- 30
- 35
- through said conduit whereby burning gas and air issuing from said mixing chamber through said apertures will heat said gas conduit to raise the temperature of the gas and air to a higher specific gravity. 40
6. A gas burner comprising a casing containing a gas mixing chamber, connected at its front end with an air passage open to the air at its opposite end, said gas mixing chamber having a plurality of apertures along its upper extremity; a gas conduit arranged over said apertures and discharging into the said gas mixing chamber; an adjustable nozzle in the discharge end of said conduit; and a valve for regulating and controlling the volume of gas passing through said conduit. 45
7. A gas burner comprising a casing containing a gas mixing chamber, connected at its front end with an air passage open to the air at its opposite end, said gas mixing chamber having a plurality of apertures along its upper extremity; a gas conduit arranged over said apertures, extending about one end of said casing and discharging into the opposite end of said gas mixing chamber; an adjustable nozzle in the discharge end of said conduit; and a valve for regulating and controlling the volume of gas passing through said conduit. 50
- 55
- 60
- 65
- In testimony whereof, I have hereunto set my hand at San Francisco, California, this 14th day of May, 1921.
- JOHN C. TATE.
- In presence of—
LINCOLN JOHNSON.
